UNITED STATES PATENT OFFICE.

DAVID C. FRANK, OF NEW YORK, N. Y., ASSIGNOR TO PELGRAM & MEYER, OF NEW YORK, N. Y., A FIRM.

DESIGN FOR A RIBBON OR NARROW FABRIC.

60,228.

Specification for Design.

Patented Jan. 17, 1922.

Application filed April 12, 1921. Serial No. 460,816. Term of patent 3½ years.

To all whom it may concern:

Be it known that I, DAVID C. FRANK, a citizen of the United States, and a resident of the city of New York, borough of Manhattan, county and State of New York, United States of America, have invented a new, original, and ornamental Design for a Ribbon or Narrow Fabric, of which the following is a specification, reference being had to the accompanying drawing, wherein—

Figure 1 is a plan view of a ribbon showing the design;

Figure 2 an end view of the same showing the contour of the design.

My design consists of a series of stripings distinguished by contrasted color and design and by texture of the fabric.

What I claim and desire to secure by Letters Patent is:

The ornamental design for a ribbon or narrow fabric substantially as shown and described.

DAVID C. FRANK.
